UNITED STATES PATENT OFFICE.

HARRY O. SPANKUS, OF MILWAUKEE, WISCONSIN.

DESIGN FOR A HANDKERCHIEF CASE.

Application filed May 7, 1923. Serial No. 6,091. Term of patent 14 years.

To all whom it may concern:

Be it known that I, HARRY O. SPANKUS, a citizen of the United States, residing at Milwaukee, in the county of Milwaukee and State of Wisconsin, have invented a new, original, and ornamental Design for Handkerchief Case, of which the following is a specification, reference being had to the accompanying drawing, forming part thereof, in which the figure is a perspective view of a handkerchief case.

I claim:—

The ornamental design for a handkerchief case, as shown.

In testimony that I claim the foregoing I have hereunto set my hand at Milwaukee, in the county of Milwaukee and State of Wisconsin.

HARRY O. SPANKUS.
